UNITED STATES PATENT OFFICE.

ROBERT HALLEY, OF CHICAGO, ILLINOIS, ASSIGNOR OF ONE-FOURTH TO
THE PLANO MANUFACTURING COMPANY, OF CHICAGO, ILLINOIS, A COR-
PORATION OF ILLINOIS.

FURNACE.

SPECIFICATION forming part of Letters Patent No. 707,103, dated August 19, 1902.

Application filed August 2, 1901. Serial No. 70,588. (No model.)

To all whom it may concern:

Be it known that I, ROBERT HALLEY, a citizen of the United States, residing in Chicago, in the county of Cook and State of Illinois, 5 have invented certain new and useful Improvements in Furnaces, of which the following is a specification.

My invention is concerned primarily with a rotatable furnace in which a plurality of 10 objects, such as tires, can be heated simultaneously, and which consists of a central stationary burner which directs a flame into a plurality of radial apertures and each aperture is adapted to receive a tire, so that the 15 operator can take out one tire that has been heated sufficiently and replace it by a fresh one. The furnace is then rotated to bring another tire to the operator, which is removed and replaced by a fresh tire, the construction 20 being such that when the furnace has made a complete rotation the tire which was placed in it at the beginning of the rotation will be sufficiently heated at the end of the rotation so that it is ready to be welded or otherwise 25 manipulated.

Referring to the accompanying sheets of drawings, in which the same reference characters represent identical parts in all the figures, Figure 1 is a plan view of the furnace 30 with the burner removed. Fig. 2 is a vertical section thereof on the line A A of Fig. 1. Fig. 3 is a plan view of one of the angle-irons forming the sides of the furnace. Fig. 4 is a plan view of the machine with all the mechanism above the bottom plate removed, and Fig. 5 is a central section through the burner on an enlarged scale.

The furnace is provided with the heavy, preferably circular, base-piece 6, which has 40 a sleeve 7 projecting upward from the center thereof, the upper portion being reduced, as shown, and provided with the shoulder 8. Centrally disposed in this base-piece is the vertical bearing-rod 9, which might be made 45 integral with the base-piece, if desired. The top of the sleeve 7 is preferably provided with the annular channel 10 therein. The bottom plate 11 of the furnace is preferably of the shape shown in Fig. 4 and has the sleeve 12 50 projecting downward from the center thereof

and fitting over the bearing 9. The bottom of the sleeve 12 is preferably provided with the annular groove or channel 13, which is opposed to the channel 10, and the antifriction-balls 14 are placed in said channels, so 55 as to insure the easy rotation of the furnace upon the base-piece. I preferably place the sleeve 15 on the outside of the reduced portions of the sleeves 7 and 12 in order to prevent any dust getting into the bearing. The 60 bottom plate 11 may be reinforced by the flanges 16, as shown in Fig. 2. The sides of the furnace are formed by the four angle-irons 17, which have the ears 18 thereon. The top of the furnace is made up of the four iron plates 65 19 of the shape shown, and these are also provided with the ears 20. The bottom plate 11 is provided with the ears 21, the ears 18, 20, and 21 being in alignment with each other, so that by passing the bolts 22 through said ears the 70 bottom plate, sides, and the top plates may be securely clamped together. The furnace-cavity thus formed is lined with the fire-brick 23 in the customary manner, and it will be seen that the openings 24 are left between the adjacent ends of the angle-pieces 17 and the fire-brick lining adjacent said angle-pieces. On the under sides of the bottom plate 11, directly opposite the openings, I bolt the Z-shaped supports 25, and a fire-brick 26 rests 80 against the support in front of the opening, partially closing it, but leaving a sufficient space to permit the entrance of the tire 27 to the opening. Another fire-brick 28 is preferably placed on the brick 27 and the upper 85 horizontal portion of the support 25 after the tire is in place. The fire-bricks forming the lining for the bottom of the furnace are preferably cut away, as shown at 29, so as to permit the flame passing down underneath the 90 edge of the tire and up against the brick 27, from which it is reflected back against the tire. Similarly the flame passes over the top of the tire and down against the fire-brick 26, so that the portion of the tire exposed to the 95 flame is very strongly heated. To support the tires, I bolt the radial angle-irons 30 to the under side of the bottom-plate 11 or any other convenient portion of the furnace, and to the upturned outer ends 31 of these angle- 100

irons I bolt or otherwise secure the iron ring 32, upon which the tire rests. As seen in Fig. 2, the burner 33 is centrally disposed in the top plates and directs the flame downward into the furnace, when it is deflected radially out to the apertures 24.

The details of the burner 33 are best shown in Fig. 5, and in Fig. 2 it will be seen that I lead a pipe 34 for compressed air to the top 10 of the burner, a pipe 35 for oil to the side of the burner, and a large pipe 36 for a blast of air from the blower to the side of the main portion of the burner. This main portion consists of a cylindrical shell 37, having at 15 one side thereof the cylindrical offset 38 with the large aperture 39 therein. A collar 40 is bolted thereto and has a flange 41, upon which the end of the pipe 36 is placed, resting against the shoulder 42. An ordinary slide- 20 valve 43 is placed in the channel between the offset 38 and the collar 40, which can be opened or closed, as may be desired, to admit or shut off the air-blast from the burner. A block 44, which has the preferably circu- 25 lar passage 45 therethrough, has its lower end 46, which is square or some similar angular shape in cross-section, taking into a similarly-shaped aperture 47 in the top of the furnace, so that as the furnace rotates the block 30 44 will rotate with it. The block 44 has a flange 48 formed thereon about midway its height, which rests on the top of the furnace when the burner is in position. Above the flange 48 the block is reduced in diameter, as 35 seen at 49, and is preferably circular in cross-section, so that it is free to rotate in the correspondingly-shaped recess 50, formed in the lower part of the block 37, which is preferably provided with a flange 51, which rests 40 upon the flange 48. With this construction of the parts it will be seen that the burner remains stationary and in the axis of the rotating furnace. The burner proper 45 consists of the tube 52, which has a screw-threaded portion 53, which is screwed into an aperture 54, formed in the top of the block 37. The end of the pipe 34 is screwed into a recess in the upper end of the tube 52 and delivers air into the channel 55, which extends 50 through the length of the burner-tube. Near its upper end the burner-tube has a cylindrical enlargement 56, through which extends transversely the plug 57, which has an L-shaped channel 58 therein, one end opening 55 to the outside and having the oil-pipe 35 screwed therein, while the other end opens on the interior of the tube 52 downwardly and has the oil-pipe extension 59 screwed or otherwise secured therein, so that the oil from the tube 60 35 passes down and is discharged from the nozzle 60. For convenience of assembling the parts I preferably make the nozzle 61 of the burner, which surrounds the nozzle 60 of the oil-pipe extension, removable, and, as seen 65 in Fig. 5, its largest interior diameter is at its upper end, which fits over the reduced end 62 of the burner-tube 52, where it is prefer-

ably secured in place by a set-screw 63. The lower end of the channel through the nozzle 61 is preferably reduced by a taper toward 70 the bottom, so that at the end of the nozzle 61 there is only a very slight annular opening around the nozzle 60.

In the operation of the burner the oil is supplied by gravity through the oil-pipe extension 59, and compressed air from the tube 34 passes down through the tube 52 and is discharged from the nozzle 61 and has a suction or atomizing effect on the oil to draw it from the nozzle 60 and to discharge it from the bottom of the burner, where it is ignited, the necessary air for combustion being supplied through the tube 36. To assist the compressed air in atomizing and breaking up the oil, I may employ the four or more pins 64, which 85 are placed in the sides of the portion 46 of the block and have their sharp points extending to the center of the channel 45 in position to receive the stream of oil and break it into particles. 90

While I have herein shown and described a preferred form of burner to be used in connection with the rotary furnace, I do not limit myself to this specific form of burner, as I may employ some other form which is capable of producing the same results, and while I have shown and described the details of said burner I do not herein claim the same, but reserve the subject-matter thereof for my divisional application, Serial No. 81,221, filed 100 November 5, 1901, covering the same.

While I have shown my invention as embodied in the form which I at present consider best adapted to carry out its purposes, it will be understood that it is capable of some modifications, and that I do not desire to be limited in the interpretation of the following claims except as may be necessitated by the state of the prior art. 105

What I claim as new, and desire to secure 110 by Letters Patent of the United States, is—

1. In a device of the class described, the combination with the stationary support, of a furnace mounted to rotate thereon having the small central open portion and the passages 115 radiating therefrom and leading to the outside of the furnace, supports for the articles to be heated adjacent to the openings terminating the passages, and a burner axially located with reference to said furnace and 120 adapted to discharge the flame into said open central portion against a solid opposed wall by which it is deflected into said passages; substantially as and for the purpose described. 125

2. In a device of the class described, the combination with the stationary support, of a furnace mounted to rotate thereon having the small central open portion and the passages radiating therefrom and leading to the outside of the furnace, supports for the articles to be heated adjacent to the openings terminating the passages, and a stationary burner having oil and air supply pipes connected 130

thereto and by which it is supported axially located in said furnace and adapted to discharge the flame into said open central portion against a solid opposed wall by which it is deflected into said passages; substantially as and for the purpose described.

3. In a device of the class described, the combination with the base having the vertical shaft 9 therein, of the bottom plate 11 having the sleeve on the under side thereof rotating upon the shaft 9, the top plates 19, the angle-irons 17 bolted between said bottom and top plates and forming the apertures 24 of the burner located in the center of the top plates.

4. In a device of the class described, the combination with the base having the vertical shaft thereon, of the furnace adapted to rotate on the vertical shaft, the radial arms 30 secured to said furnace, the ring 32 secured to said arms, and the burner centrally mounted in the top of the furnace, substantially as described.

5. In a device of the class described, the combination with the burner of the furnace

into which the flame of the burner is directed having the peripheral apertures, a support to hold articles adjacent to the apertures, and the fire-bricks cut away as at 29 to permit the flames to pass between said articles, substantially as and for the purpose described.

6. In a device of the class described, the combination with the furnace-body having the peripheral apertures, of the Z portions 25 secured to the bottom of the furnace-body 35 opposite said apertures to support the fire-bricks in front and on top of said apertures, substantially as described.

7. In a device of the class described, the combination with the block having the channel therethrough of a burner adapted to discharge a stream of oil through said channel, and a series of openings in said block having their points meeting in the said channel in the line of discharge of the stream of oil, substantially as and for the purpose described.
